UNITED STATES PATENT OFFICE.

JOHN A. BELL, OF LOS ANGELES, CALIFORNIA, ASSIGNOR TO RAILWAY SPECIALTIES COMPANY, OF LOS ANGELES, CALIFORNIA, A CORPORATION OF CALIFORNIA.

WIGWAG FLAGMAN.

1,134,071.

Specification of Letters Patent. Patented Mar. 30, 1915.

Application filed January 31, 1914. Serial No. 815,825.

To all whom it may concern:

Be it known that I, JOHN A. BELL, a citizen of the United States, residing at Los Angeles, in the county of Los Angeles and 5 State of California, have invented a new and useful Wigwag Flagman, of which the following is a specification.

This invention relates to electrically operated railway signals in which the signal is 10 given a constant movement to attract attention, while it is indicating danger. In previous devices of this character the movable signal has been actuated by solenoids which 15 actuated a mechanism so arranged that the signal was abruptly stopped at each end of its stroke by positive fixed mechanical means, which caused a jar and shock to the mechanism and interrupted the natural swinging motion of the signal. 20 The main object of the present invention is to allow the signal and its armature to swing freely, without hitting any fixed mechanical stop at each end of its stroke, to employ magnets for giving the necessary 25 oscillation to the armature and signal, and to stop the swinging of the signal at the end of each stroke by cutting off the circuit of the magnet which was pulling in that direction, and close the circuit through the magnet to pull it in the opposite direction. Thus 30 reversal of the oscillating armature and signal at each end of the stroke is produced magnetically, thereby avoiding shock to the mechanism and imparting a natural free 35 movement to the armature and signal, allowing them to operate after the manner of a pendulum and requiring the least possible energy for operation.

A further object is to provide an improved switch which will not rapidly burn off in use.

Another object is to cause the bell to oscillate on the swinging frame to improve the ringing thereof.

Other objects and advantages will be brought out in the following description:

Referring to the drawings: Figure 1 is a front elevation of the signal, complete. Fig. 2 is a side elevation of the complete signal. Fig. 3 is an enlarged side elevation of that portion of the magnetic operating mechanism which is inclosed, the nearest half of the inclosing case being removed. Fig. 4 is an enlarged section on line x^4-x^4 , Fig. 3. 55 Fig. 5 is an enlarged section on line x^5-x^5 ,

Fig. 3. Fig. 6 is an enlarged section on line x^6-x^6 , Fig. 5. Fig. 7 is a diagrammatical view of the connections, showing one position of the parts. Fig. 8 is a view similar to Fig. 7, showing another position of the parts. Fig. 9 is a view similar to Fig. 5, showing a modified form, with the parts in one position. Fig. 10 is a view similar to Fig. 9, showing the parts in the opposite position. Fig. 11 is a diagrammatical view of the three-point switch. Fig. 12 is a detail view of the reversing mechanism of Fig. 9. Referring to Figs. 1 to 8 inclusive, 1 designates the signal which is here shown as in the form of a disk with the warning sign 70 printed thereon. This signal is secured between two arms 2. These arms are spread apart above the signal 1 and their upper ends are secured to an oscillating armature 3, having trunnions 4 which are journaled 75 in bearings 5 in a case 6, which is constructed of two sections which separate through the bearings 5, and swinging doors 7 are arranged in each end of the case to give ready access to the interior, each door having an 80 upwardly projecting flange 8, received in a rabbeted portion in the case, and having an inclined lower flange 9 which fits against a correspondingly beveled portion of the case, to exclude water and dust. 85

Two pairs of magnets are arranged within the case, one pair 10 being arranged on one side of the case, and the other pair 11 being arranged on the other side, the two pairs of magnets being at an angle to each 90 other and being retained in position by cores 12 retained by set screws 13, the two sets of magnets and their cores being arranged radially to the axis of the armature 3, and the lower ends of the cores being so 95 positioned that the armature is free to swing close thereunder without striking the cores, the line of movement of the armature being transverse to the axis of the core of the magnet. This is an important feature of 100 the invention. In other devices of like nature, the armature movement is in a direction in line with the axis of the solenoid, such that it would strike the solenoid were it not positively interrupted. The present 105 construction permits a free swinging of the armature across the ends of the magnets and its movement is unimpeded by any obstruction and it is not stopped at the limit of each stroke by any mechanical abutment, 110

its reversal of stroke being produced by breaking the circuit through the magnet which is attracting the armature and closing the circuit through the opposite magnet to cause the armature to be stopped and attracted in the opposite direction. Thus the complete movement and control of the armature is performed magnetically, its movement being performed magnetically and its reversal of movement at the end of each stroke, likewise being performed magnetically.

In order to control the circuits through the magnets two switches 14 and 15 are provided, each switch consisting of a plurality of carbon contact points 16 which are supported in tubes 17, mounted in an insulating base 18 which is attached to an insulating plate 19. Slidable in each base 18 is a stem 20 which is located centrally between the contacts 16. There may be two contacts 16, or three contacts 16^a as shown in Fig. 11, and in either case the stem 20 is located centrally between them. Each stem 20 carries a disk 21 which is adapted to descend into contact with the contacts 14 and each stem 20 projects below the base 18. A rock arm 22 is pivoted on a stationary stud 23 and is adapted to alternately actuate the stems 20. The rock arm 22 has a notch 24 and a tongue 25 projects from the armature 3 into the notch 24, and as the armature swings, the tongue is alternately brought against opposite sides of the notch and tilts the rock arm 22 accordingly. An S-spring 26 is arranged above the rock arm 22, the lower end of the spring being pivoted at 27 to the rock arm, the upper end of the spring 26 being received in a slotted post 28.

Figs. 7 and 8 diagrammatically illustrate the operation of the device. When one of the switches is depressed, for instance, the switch 15 as shown in Fig. 7, it closes the circuit through the magnet 10, which attracts the armature toward it and swings the signal from the position shown in Fig. 7, to the position shown in Fig. 8, and as the tongue 25 strikes the wall of the notch 24, it occurs when the signal has nearly reached its extreme left hand position, which tilts the rock arm 22 from the position shown in Fig. 7 to the position shown in Fig. 8, thereupon breaking the circuit through the magnet 10 and closing the circuit through the magnet 11, and as soon as this occurs, the armature is attracted in the opposite direction and the signal is accordingly oscillated in the opposite direction. The width of the notch 24 is such that the rock arm 22 remains stationary during practically the entire movement of the armature, except for a slight amount of movement at each end of the stroke, which takes place during the shifting of the switches and the reversal of the signal.

Located at a point above the signal 1 and between the arms 2 is a bell suspended from a cross bar 30 which is pivoted to clamps 31 on the bars 2, and a rigid finger 32 projects slidably into a pivoted cross rod 32'. As the signal is oscillated the bell 29 by reason of its pivotal mounting on the frame and engagement of finger 32 is given an axial movement which causes a proper swinging action of its tongue and gives a much better warning than if the bell were mounted rigidly on the frame 2.

When three contact points 16^a are employed as in Fig. 11, two of them are connected as by wire 33 with one side of the circuit, for example, the positive side 34, while the other single contact point 16^a is connected with the opposite or negative side 35. As before explained, these three contacts are uniformly spaced around the sliding stem 20 of the switch and when the switch disk 21 falls it is supported at three points. On account of there being two positive contacts, the current is divided and the contact points do not burn off so rapidly. The negative contact point does not burn at all. In addition to this advantage the three contact points give a more even support for the disk than when only two contacts are employed.

If desired, the modification shown in Figs. 9, 10 and 12 may be employed. In this form the rock arm is not directly actuated by the armature, but is indirectly actuated through the medium of an intermediate lever 36 which is pivoted on the stud 23, but is movable independently of the rock arm 22^a. The S-spring 26^a instead of having its upper end secured to a stationary point, as in the previous form, has its upper end pivotally connected at 37 to the upper end of the intermediate lever 36. The intermediate lever 36 has a forked lower end with lugs 38 and 39 adapted to be alternately operated by the tongue 25. As the armature swings to the right as shown in Fig. 9, it moves the signal to the left and moves the tongue 25 to the right, and upon reaching the position shown in Fig. 9, the tongue 25 acts against lug 39 to swing said lug 39 slightly to the right, moving the upper end of intermediate lever 36 to the left. Owing to the greater length of the upper portion of the intermediate lever above the pivot 23, only a slight movement of the lug 39 is sufficient to swing the upper end of the intermediate lever 36 across the center line, whereupon the S-spring 26^a operates to automatically swing the intermediate lever 36 into the position shown in Fig. 10 and as the point 37 passes the lower pivotal point of the S-spring 26^a, it causes the spring to oscillate the rock arm 22 in the reverse direction and shift the switches 18 and 19, whereupon the armature is swung in the opposite direction and when the parts

reach the position shown in Fig. 10, the tongue 25 acts against lug 38 to swing the upper point 37 of the intermediate lever to the right, and the spring 26* completes the 5 movement and reverses the position of rock arm 22 and correspondingly actuates the switches 18 and 19.

What I claim is:

1. A case formed in two sections united at 10 the middle, a magnet core detachably secured in each section, a magnet on each core, means securing the sections detachably together, the two sections having journal bearings, the center line through said journal 15 bearings meeting the axial lines of the cores at their points of intersection, the said bearings being divided by the line of division between the two sections, an armature mounted in the said journal bearings and 20 having a free movement with respect to said cores, a signal carried by said armature, and switch means located within said case and operated by the movement of the armature for controlling the circuits through the said 25 magnets to reverse the direction of movement of the armature at each end of its stroke.

2. In a wig-wag flagman, a case, arms projecting from the case, a signal carried by 30 said arms, mechanism within said case for oscillating said arms, and a bell mounted between said arms and between the signal and case to be rung by the movement of the arms.

3. In a wig-wag flagman, a case, arms projecting from the case, a signal carried by 35 said arms, mechanism within said case for oscillating said arms, a bell mounted between said arms and between the signal and case to be rung by the movement of the arms, and swinging doors in opposite ends 40 of the case, giving access thereto, said case being in two sections, detachably secured together, said doors extending over both sections.

4. A pivoted armature provided with two radial sockets, a pair of arms projecting into

said sockets, a signal carried by said arms, magnets for attracting said armature in opposite directions, a case inclosing said magnets and armature, a base in said case, a rock arm pivoted on said base and having a notch, a tongue on the armature projecting into said notch, switch contacts supported by said base, switch stems extending slidably between said contacts, a disk carried by each stem, and adapted to rest upon the associated contacts when the stem is lowered, said stems being actuated by said rock arm. 50

5. A pivoted armature provided with two 6 radial sockets, a pair of arms projecting into said sockets, a signal carried by said arms, magnets for attracting said armature in opposite directions, a case inclosing said magnets and armature, a base in said case, a rock 65 arm pivoted on said base and having a notch, a tongue on the armature projecting into said notch switch contacts supported by said base, switch stems extending slidably between said contacts, a disk carried by each 70 stem, and adapted to rest upon the associated contacts when the stem is lowered, said stems being actuated by said rock arm, there being three contacts around each stem, two of said contacts being connected with 75 one side of the circuit through the associated magnet, and the other contact being connected with the opposite side of the circuit whereby burning of the contacts is minimized. 80

6. In a wig-wag flagman, a case, a frame pivoted to the case, a signal carried by the frame, a bell pivoted on said frame, and a connection between the bell and case for causing the bell to oscillate axially with respect to said frame when the frame is oscillated. 85

In testimony whereof, I have hereunto set my hand at Los Angeles, California, this 16th day of January, 1914.

JOHN A. BELL.
